JAMES MCKECHNIE, OF BARROW-IN-FURNESS, ENGLAND, ASSIGNOR TO VICKERS
LIMITED, OF WESTMINSTER, LONDON, ENGLAND.

RECIPROCATING ENGINE.

1,419,159.

Specification of Letters Patent. Patented June 13, 1922.

Application filed October 6, 1920. Serial No. 415,165.

(GRANTED UNDER THE PROVISIONS OF THE ACT OF MARCH 3, 1921, 41 STAT. L., 1313.)

To all whom it may concern:

Be it known that I, JAMES MCKECHNIE, a subject of the King of Great Britain, residing at Naval Construction Works, Barrow-in-Furness, in the county of Lancaster, England, have invented certain new and useful Improvements in or Relating to Reciprocating Engines (for which I have filed an application in Great Britain, No. 23,028, 10 Sept. 18, 1919, Patent No. 165,861), of which the following is a specification.

This invention relates to reciprocating engines, such as internal combustion or steam engines, of the type employing opposed pistons in a common cylinder and connected to a common crank shaft.

The chief object of the invention is to reduce to a minimum the unbalanced stresses due to the movements of the large masses of the various engine members, more especially the secondary or lateral stresses which in engines of this class as hitherto constructed are of a substantial nature, although the longitudinal stresses are largely balanced by 25 the opposing action of the pistons.

According to this invention each one of a pair of cylinders carries a pair of oppositely acting pistons with a common working space between them, the said pistons being connected to the ends of a pair of rocking levers placed at opposite ends of the cylinders and connected to each other at one end through a link, a connecting rod attached to the link or to one of the levers 30 driving the crank of the engine shaft. The end of the connecting rod may be guided by a slide working in a guide in the engine casting between the two cylinders or, if the links connecting the rod to the rocking 35 levers are constructed as a single member extending from one lever to the other, this member may withstand the comparatively small side stresses, which are then borne by the trunnions of the rocking levers.

The links between the levers and the connecting rod are subjected both to tension and compression, but compression may be avoided by connecting the opposite ends of the rocking levers by a tension rod independent of the connecting rod. The working 50 strokes of the two cylinders alternate, the pistons in one cylinder performing their in-

ward stroke while the other pistons are on their outward stroke.

In order that the said invention may be clearly understood and readily carried into effect we will now describe the same more fully with reference to the accompanying drawings, in which:

Figure 1 is a sectional elevation of a construction of internal combustion engine embodying this invention.

Figure 1^a is a sectional elevation at right angles to Figure 1, Figure 1^b is a plan of the engine;

Figures 2 to 8 are diagrammatic elevations of a series of modifications of the engine.

A, A are the cylinders. B, B¹ are the top and bottom pistons, a pair of pistons working in each cylinder. C, C¹ are the top and bottom rocking levers connected to the pistons by the connecting rods b. D is the link connecting crosswise the opposite ends of the top and bottom levers C, C¹ through the pivot pins C^x. E is the crank shaft. F is the connecting rod driving the shaft E. The rocking levers and links are duplicated for purposes of symmetry and balance.

Referring to the arrangement shown in Figs. 1, 1^a and 1^b, the cylinders A are shown symmetrically placed on each side of the crank shaft E, to the crank pin e of which is secured the outer end of the connecting rod F, the upper or inner end of which is provided with the crosshead f on the cross pin d of the link D. The crosshead is shown with the slipper bars f¹ sliding between guides g on the engine casing G, so that any side stresses which may arise are taken by the guides and the engine casing on the frame G', which is mounted on the base G², the latter carrying the bearings g¹ for the shaft E.

The lower lever C¹ is pivotally mounted on trunnions c carried by the frame G¹ and the upper lever C is mounted on trunnions c¹ carried by the bracket or upper frame G² which is connected to the base G² by the tie rods g². The upper arm of the link D is shown as larger than the lower arm and the pistons B, B¹ are shown unsymmetrically placed in their cylinders A so that the exhaust ports a¹ leading to the exhaust outlet

a^2 at the upper end of the cylinders are uncovered before the inlet ports a^3 leading from the air inlet a^4 at the lower end of the cylinder. The levers C, C' and link D are 5 each duplicated, as already mentioned, and as shown in Figs. 1^a and 1^b, for purposes of symmetry and balance, the connecting rod F being single and therefore placed centrally of the engine between the two pairs of lever and link members.

The engine operates on ordinary two stroke lines, but the flow of gases is, as is in the known opposed piston type of engine, always in the same direction, the air entering at one end of the piston and the gases 15 exhausting at the other. The use of a connecting rod for driving the shaft enables a very compact form of engine to be designed, with the cylinders close together and the 20 crank shaft in any position that may be desirable. The secondary stresses due to unbalanced inertia forces are reduced to a minimum by the combination of cross connected rocking levers with a connecting rod 25 drive for the shaft. The inner end of the connecting rod moves in a practically straight line parallel to the cylinders and any side stresses that may occur due to the angle of the connecting rod at half way positions can be taken by the guides g and 30 therefore by the main frame of the engine.

In the modification shown diagrammatically in Figures 2 and 3 the rocking levers C, C' at each end of the cylinders A are 35 double (see Figure 3) and a pair of links D is provided, one at each side of the cylinders, the cross pin d connecting the two links at the middle and providing for the attachment of two connecting rods F driving 40 a pair of cranks e on the crank shaft E. The cross pin and the ends of the connecting rods may be attached to one side of the link as shown in Figure 2, the crank shaft E being correspondingly displaced from the 45 centre line of the engine.

In the modification shown in Figure 4 twin crank shafts E¹ are employed and the two connecting rods F¹ connect to the opposite ends of the lower rocking lever C¹ instead of directly to the link D. Or as shown in Figure 5 the connecting rods F¹ may be attached to the opposite ends of a rocking lever C² carried on the shaft c¹ of the upper piston driven rocking lever C, the connecting rod lever C² extending beyond the cylinders A so as to allow the connecting rods F¹ to clear the latter. The twin shafts E¹ in this case are placed outside the line of the cylinders.

60 According to a further modification shown in Figure 6 the connecting rod F² for a shaft E² placed at one side of the engine may be attached to an arm or lug c² on the lower rocking lever C¹, to which arm c² the 65 rocking lever link D may also be connected,

the opposite rocking lever C having a corresponding arm or lug c³ for attachment of the other end of the link.

We may also, as shown in Figures 7 and 8, employ a single connecting rod F and 70 crank e for two pairs of cylinders A¹ placed side by side, the pin d² of the connecting rod F passing through the center of the rocking lever links D belonging to the engine unit on each side of the rod. This arrangement is preferably employed, as shown, with two pairs of links D and corresponding rocking arms C, C¹ for each unit, 75

An internal combustion engine of the ordinary type of say, 300 to 400 brake horse 80 power, single cylinder, would require water cooled pistons, but with this arrangement cylinders of sufficiently small diameter can be utilized to develop the same horse power and render water cooling of their pistons 85 unnecessary, and for the powers above this oil cooling might be adopted, and only water cooling would be required for larger cylinders of, say, over 12" diameter for two-stroke engines, or over 17" diameter for 90 four-stroke engines.

What I claim and desire to secure by Letters Patent of the United States is:—

1. In a reciprocating engine, a pair of cylinders, a pair of oppositely acting pistons in each cylinder, a pair of rocking levers one at each end of the cylinders, driving connections from the said rocking levers to the four pistons, a rigid link connecting diagonally the two rocking levers, a crank 100 shaft and a connecting rod interposed between the said shaft and the rocking lever-link system and driving the shaft from the said system.

2. In a reciprocating engine, a pair of 105 cylinders, a pair of oppositely acting pistons in each cylinder, a pair of rocking levers one at each end of the cylinders, driving connections from the said rocking levers to the four pistons, a rigid link connecting 110 diagonally the two rocking levers, a guide maintaining the path of the middle of the link substantially parallel with the axes of the cylinders, a crank shaft and a connecting rod interposed between the said shaft 115 and the rocking lever-link system and driving the shaft from the said system.

3. In a reciprocating engine, a pair of cylinders, a pair of oppositely acting pistons in each cylinder, a pair of rocking levers one at each end of the cylinders, driving connections from the said rocking levers to the four pistons, a rigid link connecting diagonally the two rocking levers, a crank 120 shaft, and a connecting rod driving the crank shaft which rod is pivotally connected at its other end to the middle of the diagonal link whereby the pivoted end of the rod moves in a substantially straight path parallel to the axes of the cylinder. 125 130

4. In a reciprocating engine, a pair of cylinders, a pair of oppositely acting pistons in each cylinder, a pair of rocking lever members on a fixed fulcrum at one end of the cylinders, piston connecting rods from the pair of pistons at the same end to the opposite ends of the said lever members, a second pair of rocking lever members at the opposite end of the cylinders, fulcrum pins for the said members, piston connecting rods from the second pair of pistons to the ends of the second pair of lever members, a pair of connecting links connected diagonally to opposite ends of the two pairs of rocking lever members, a crank shaft and a central connecting rod driving the said crank shaft, which rod is connected to the middle of the pair of diagonal links and lies between the second pair of rocking lever members. 20
5. In a reciprocating engine, a pair of parallel cylinders, a pair of oppositely acting pistons in each cylinder, interconnecting members between the pistons of both cylinders including a rigid diagonal link between the pistons at opposite ends of the two cylinders, a crank shaft and a connecting rod connected to about the middle of the said diagonal link and driving the said crank shaft. 25
- 10 15 20 25 30

In testimony whereof I affix my signature.
JAMES McKECHNIE.
